RECTILINEAR WARP KNITTING MACHINE

Marcel Vitek, Geneva, Switzerland

Application June 24, 1948, Serial No. 34,965
In Switzerland July 10, 1947

3 Claims. (Cl. 66—86)

1

The rectilinear warp knitting machines known to date include the following main elements: one needle bar, one sinker bar, one press bar, one thread guide bar.

The machines which do not include a press are fitted with a complementary needle bar.

The mesh formation is obtained by drawing each of these bars in individual, periodical to and fro movements synchronised one with the other.

From this fact arise four basic movements generally controlled by cams carried by a cam-shaft. However, it is not an unusual thing to come across machines including two or several camshafts. In order to transmit to the respective bars the movements of the pushers acting in conjunction with the cams, the known machines require, in addition, a set of carrier-levers, an individual shaft for each movement and, in many cases, from 1 to 8 complementary pivoting points for the transmission and auxiliary parts.

When one considers the best possible design for a machine based on the principle of the known machines, one obtains at least five shafts, viz.: one camshaft, one shaft controlling the needles, one shaft controlling the sinkers, one shaft controlling the press, one shaft controlling the thread guides.

The plurality of these shafts, which are by necessity comparatively distant one from the other, leads unavoidably to a complicated and expensive mechanical realisation, while favouring vibrations which are harmful to the correct working of the machine.

The present invention relates to a rectilinear warp knitting machine including a needle bar, a sinker bar, a thread guide bar and a press driven in synchronised periodical movements one with the other by revolving controlling parts.

This machine aims at eliminating the above mentioned drawbacks by the fact that it includes only two main shafts and at most one auxiliary shaft, the first main shaft being revolving and carrying all said revolving controlling parts, and the second main shaft being fixed and carrying sets of oscillating arms at the end of which are fixed at least the sinker bar and the press, and by the fact that the needle bar is fixed on a set of carriers mounted on the two main shafts and driven by a set of revolving controlling parts, while the thread guide bars are driven in their floating motion by a set of levers, oscillating on the fixed shaft and carrying driving parts acting in conjunction with a set of revolving controlling parts.

2

The attached drawing shows diagrammatically and by way of example two forms of embodiment of the knitting machine.

The Fig. 1 is a part profile view of a first embodiment of the knitting machine.

The Fig. 2 is a part cross-section view along the line II—II of the Fig. 1.

The Fig. 3 is a profile view, the frame being removed for the drawing's clearness sake.

10 The Fig. 4 is a view of the needle bar controlling device.

Fig. 5 is a part view in plane.

The Figs. 6 and 7 are part profile views showing press and the sinker bar with their controlling devices.

15 The Fig. 8 is a part profile view of a second embodiment.

The Figs. 9 and 10 are detail views.

20 The Fig. 11 is a diagram showing the synchronised displacements performed by the various parts of the knitting machine.

In accordance with the embodiment shown on the Figs. 1 to 7, the knitting machine has a frame 2 including machined supporting surfaces 25 intended for fastening bearing supports 3. Each of said supports has a bearing head 5 for a revolving shaft R and a housing for a fixed shaft F clamped in position by means of a collar 4. These shafts R and F are therefore carried by both their ends and constitute the main shafts 30 of the knitting machine. According to the knitting machine length, intermediate supports 3 can be provided for.

25 The fixed shaft F carries:

35 (1) two sets of oscillating arms 6 and 7 (Figs. 6 and 7) at the ends of which are respectively fastened the press 8 and the sinker holders 9 by means of the bars 10 and 11;

40 (2) a set of levers 18 (Fig. 3) carrying each a controlling part 19 acting in conjunction with a revolving cam means 20 rigidly fixed on the revolving shaft R.

45 Each of the arms 6, 7, carries a controlling part 12, 13, acting each in conjunction with a revolving controlling cam means 14, 15, rigidly fixed on the revolving shaft R. Each controlling part 14, 15, 20, is constituted by a disc having a groove 16, 17, 21, made in one of its lateral faces.

50 The levers or arms 18 are mechanically linked to an auxiliary shaft A, carrying the thread guide leads 22, 23. These latter are each rigidly fixed on a bar 24, 25 constituted by a slider, both sliding in a slide 26, 27 which are both rigidly fas-

tended to the end of arms 28, 29 carried by the auxiliary shaft A. The arms 29 are rigidly fastened on the shaft A by means of stopping parts 30 and have each a groove 31 (Fig. 5) made in one of the front faces of their hub 32. The arms 28 each have a hub 35 drilled with an oval hole 33 intended for the passage of the shaft A, and having on one of its front faces a rib 34 engaged in the groove 31 of the adjoining hub 32. A ring 55, fixed on the shaft A by means of a blocking part, fixes the axial position of the arm 28 and keeps the rib 34 engaged in the groove 31. The oscillating movement of the thread guide bars is imparted to the latter by one or several levers 37 rigidly fixed on the shaft A and connected by rods 38 to the arms 18. The attachment point of each rod 38 on each lever 37 is adjustable by means of an articulation axle 39 engaged in a port 40 of the lever 37 and of which the position in said port can be chosen and fixed by means of standard type clamping parts not represented.

The hub 35 has a boss 41 carrying a shank 42 engaged in a fork 43 provided at the end of a lever 44 rigidly fixed on an axle 45 housed in the frame. The latter also carries a hand controlling part of standard type not represented. The needle bar 46 is rigidly fixed on carriers 59, carrying each:

(1) a controlling part 52 acting in conjunction with a revolving controlling cam means 47 rigidly fixed on the revolving shaft R. This controlling cam means is constituted by a disc having on one of its front surfaces a groove 53 in which is engaged the part 52;

(2) a guiding part constituted by a tube 48 sliding inside a sleeve 49 carried by the shaft R by means of a flange 54 and fixed rigidly to the fixed shaft F by means of a carrier 50. The tube 48 is guided within the sleeve 49 by means of two rings 51.

The working of the above described knitting machine, with reference to Figs. 1 to 7 of the drawing, is similar to that of known knitting machines.

When the revolving shaft R is driven in rotation, the controlling parts which it carries impart to the main parts of the knitting machine the synchronised displacements illustrated by the graphs of the Fig. 11. On this figure, the magnitude of the displacements of the knitting machine's main parts effecting periodical to and fro movements, are plotted vertically and as a function of the rotation angle of the revolving shaft plotted horizontally.

The graph *a* represents the motion of the needle bar; the graph *b*, the floating motion of the thread guide bars; the graph *c* that of the sinker bar and the graph *d* that of the press. It is obvious that the form of each groove must be computed very accurately in order to obtain the displacements represented on the Fig. 11, and moreover, the discs must be angularly fastened on the shaft R in relative positions such that, for any angular position of the revolving shaft R, each part is actually in the position indicated by the graph of the Fig. 11. It is obvious that the thread guide bars are controlled in a way parallel to the auxiliary shaft A by means of a pusher, in the same manner as in knitting machines of known types. The pushers act at the end of the bars 24 and 25. These longitudinal displacements of the thread guide bars can take place, for instance, between 110° and 170°, while the thread guides are behind

the needles and between 300° and 20°, when the thread guides are in front of the needles.

The arms 28 can be lifted by hand operation of the axle 45 by means of its controlling part, so as to lift the bar 24 carrying the thread guides 22 and thus give access to the ends of the thread guides 23 and allow to pass threads in each of their holes, when breaking of the threads of this bar has taken place.

If one wants to lift entirely the thread guide bar 22, it is sufficient to unblock the ring 55 in order to clear the rib 34 from the groove 31 and to lift the arms 28 in causing same to revolve around the auxiliary shaft A.

Study of the attached drawing will show that the design of the described knitting machine is much simpler than that of the known knitting machines. Indeed, all the controlling parts of the knitting machine parts performing periodical to and fro movements are mounted on the same revolving shaft. This shaft R is very rigidly mounted on the frame by means of the support 3 which carries also the fixed shaft F. The distance between these two main shafts is comparatively small, so that it is easy to secure all the wanted rigidity. As to the auxiliary shaft, it revolves in bearings 14 rigidly fixed to the frame. This shaft A carries the two thread guide bars by means of the arms 28 and 29, on which are rigidly fixed the slides 26 and 27, such arrangement leading to design simplification and to render the whole much more rigid than is the case in known designs, while requiring only a much smaller force to provoke the longitudinal displacements of the thread guides 22 and 23.

Indeed, in the known knitting machines, each thread guide bar is fixed to a suspension apparatus permitting, on one hand, the oscillating movement of the thread guides, and on the other hand, their longitudinal displacements. It follows that these bars are carried only by a few points remote one from the other, this number of carrying points and their distance being variable in accordance with the number of suspension arms provided for. In addition, these thread guide bars have necessarily a transversal cross section of general rectangular shape, comparatively high and narrow. In view of the high working speeds wanted on modern knitting machines, this kind of suspension for the thread guide bars is no longer sufficient. Indeed, these bars vibrate and thereby undergo permanent longitudinal deformations in their parts situated between the suspension arms. In addition, the latter lack rigidity and on the other hand, their guiding point on the auxiliary shaft is too remote from the ends of the thread guides loaded with the threads to permit achieving the necessary accuracy in the longitudinal positions of the thread guides and, moreover, jammings take place which are the cause of a longitudinal displacement of the thread guides occurring in a jerky manner and therefore harmful to the proper working of the knitting machine.

On the contrary, in the described knitting machine, the slides 26, 27 are rigidly fixed on the arms 28, 29 at the height and approximately in the thread guide bars horizontal transversal plane. Moreover, these slides 26, 27 constitute guides for the thread guide bars 25, 24, which are constituted by sliders of which the maximum rigidity plane in respect of bending is approximately perpendicular to the oscillation plane of the thread guides, so that they cannot practically

undergo longitudinal permanent deformations, inasmuch that they can be supported by guides 56 of which the number can be chosen as great as necessary in order to avoid any harmful longitudinal vibration. Finally, only the thread guide bars 24, 25 are longitudinally driven by pushers (not shown), for the formation of the various patterns wanted.

From this aggregate of advantageous conditions, there result on one hand a very great simplification in the design of the knitting machine, and the certainty of avoiding longitudinal vibrations as well as any trepidation, so that this design enables one to increase the working speed of the knitting machine with respect to the maximum working speed of knitting machines of known design, while ensuring enough accuracy in the motions to avoid untimely breaking of the warp threads.

Another advantage of the described knitting machine arises from the fact that its main organs constitute together, with their controlling parts, the main shafts and the auxiliary shaft, a removable aggregate. This feature enables one to perform the setting of the knitting machine at the factory, then to take out, for transportation purposes, the said aggregate from the frame. When received, this aggregate can be mounted by non-specialised fitters, since it is sufficient to fasten this aggregate on the frame by means of the carriers 3 to obtain a knitting machine fully set and meeting the wanted requirements.

In the embodiment represented on the Figs. 8 to 10, the knitting machine includes two main shafts, of which one F is fixed and the other R revolving. These shafts are kept in relative defined positions by a carrier rigidly fastened on the frame 2.

On the other hand, this knitting machine includes no auxiliary shaft, but only articulation axles 60 enabling to lift one of the thread guide bars in order to give access to the rear thread guides.

The revolving shaft R carries all the controlling parts of the main organs of the machine performing periodical to and fro movements synchronised one with the other. Each controlling part is constituted by a disc having a groove made in one of its front faces.

The fixed shaft F carries:

(1) three sets of oscillating arms 6, 7, 61, at the ends of which are fixed in a rigid manner, respectively the press 8, the sinker holders 9 and the thread guide leads 23, by means of the respective bars 10, 11 and 25;

(2) a set of levers 62 carrying each a controlling part 52 acting with the grooves 53 of the discs 47 operating the displacements of the needle bar 46.

The bar 24 carrying the thread guides 22 is fixed by means of the slide 26 on a set of articulated arms 63 articulated on the set of arms 61 by means of articulation axles 60 carried by the arms 61. This set of arms 63 is kept intermediate its two extreme positions (working position represented by the drawing, and lifted position) by means of a tipping device. The latter includes a compression spring 64, one of the ends of which rests on a part 65 of a tip-over casing. This latter is articulated by means of an axle 67 on an extension 75 of the oscillating arm 61, carrying a slide 27 in which is mounted the thread guide bar 25. The other end of this spring 64 acts on a sliding part 68 guided by the walls 69 of the tip-over casing. This sliding part 68

carries a contact roller revolving freely on an axle 71 and rolling along the curved runway 72 provided on the arm 63. This curved runway is so arranged that the distance a is greater than the distance b for the thread guides 22 working position (position represented on the drawing). This position is defined by stops (not shown) fixed on each of the arms 63 and acting in conjunction with a part of each of the oscillating arms 61.

In order to lift the thread guides 22, it is sufficient therefore to exert an upward push on the bar 26, so as to displace it angularly against the action of the spring 64. When, owing to this angular displacement, the distance a has become smaller than the distance b, the spring relaxes and the contact roller 70 rolls along the curved runway 72, provoking the complete oscillation of the set of arms 63, that is to say up to its second extreme position defined by stops (not shown).

The needle bar 46 is carried by carriers 80 mechanically linked by small rods 81 to the levers 62. The carriers 80 are constituted by arms revolving freely on the revolving shaft. Thus, these arms are guided by the revolving shaft and are driven in a to and fro movement by the controlling part 52 acting in conjunction with the controlling part of the needle bar.

The mounting of the thread guide bars 24 and 25 is similar to that described with reference to the Fig. 3.

In this embodiment, the knitting machine includes no auxiliary shaft, so that a very sturdy and simple design including only two main shafts is obtained.

These main shafts constitute, with the main organs of the knitting machine and their controlling parts, a removable aggregate fixed on the frame by means of supports 3. This aggregate fully mounted and set before-hand can thus be shipped independently from the frame, so that it is no longer necessary to call specialists for the mounting on the spot and the starting of the knitting machine.

From above explanation and by referring to the attached drawing, one sees that the described knitting machine has, among others, the following advantages: great simplification from the mechanical point of view of the aggregate formed by the controlling and driving parts required for the formation of the meshes, thus permitting to design this aggregate as a single block to be fastened on the knitting machine's frame by means of double bearing carriers.

This feature offers a considerable advantage when dismounting and remounting the knitting machine, owing to the fact that all the parts constituting the block remain in their working position, so that any adjustment work when the remounting takes place is unnecessary. It follows that this mounting does not call for a fitter from the manufacturer.

Due to the fact that each bar is set in motion by so many cams as it has fastening parts, the pressure exerted on the cams is reduced in proportion, while this pressure is distributed in an even way on the whole length of the knitting machine, thus permitting a more regular and lighter running of the knitting machine while reducing the vibrations and the wear and tear of the mechanical parts.

The embodiment shown on the Fig. 8 clearly demonstrates how, by the present invention, the various movements of the bars can be provoked in the most direct way, and therefore the simplest,

while giving the greatest possible guarantee from the accuracy of the movements point of view, in reducing to the minimum any possibility of floating or vibration.

The embodiments above described present cams with inside curves, of which the advantage lay in the fact that it simplifies the controlling devices since they require only a single controlling part (contact roller), which favours the adjustment of the bars without entailing the well known drawback, provoked by the system making use of the cam with a counter-cam and two contact rollers, which consists in a jamming between the cams and the contact rollers at certain stages of the rotation, while producing some slack at other stages.

In order to permit the passage of the two thread warps through the set of arms 28, or 63, the latter have a V-shaped portion at the place of passage of the warp threads.

It is obvious that the two embodiments here-with described by way of example can be readily adapted to the various required working conditions and that the described parts and devices can be directly replaced by their equivalents.

I claim:

1. A rectilinear warp knitting machine, comprising, a frame, a main shaft fixed in the frame, two sets of arms fulcrumed on the main shaft for oscillating movement, a second main shaft rotatable in the frame, two cam means fixed on the rotatable shaft and each engaging an arm

to oscillate same, press means carried by one set of arms, sinker means carried by the other set of arms, a needle bar, carrier means fixed to the needle bar and fulcrumed upon the fixed main shaft, a third cam means rotatable with the rotatable main shaft and oscillating the carrier means, a third set of arms fulcrumed upon the fixed main shaft, a fourth cam means rotatable with the rotatable shaft and oscillating the third set of arms, and thread guide supporting means mounted on the third set of arms.

2. The knitting machine according to claim 1 and wherein, the thread guide supporting means comprises two thread guide supports and one of the thread guide supports is rigid with the third set of arms and the other thread guide support is pivoted to the ends of the third set of arms for swinging between two limits, and yieldable means tending to hold the second thread guide supports in either of the two limit positions.

3. The knitting machine according to claim 1 and also comprising an auxiliary shaft mounting the thread guide supporting means.

MARCEL VITEK.
